THERMOMETER SUPPORT

Joseph J. Milavec, Cleveland, Ohio

Application March 29, 1949, Serial No. 1,701

Term of patent 14 years

(Cl. D52—7)

To all whom it may concern:

Be it known that I, Joseph J. Milavec, a citizen of the United States, residing at Cleveland, in the county of Cuyahoga, and State of Ohio, have invented a new, original, and ornamental Design for a Thermometer Support, of which the following is a specification, reference being had to the accompanying drawing, forming part thereof, and wherein:

Fig. 1 is a front elevational view of a thermometer support, showing my new design; and

Fig. 2 is a side elevational view of the thermometer support shown in Fig. 1.

The characteristic features of my design reside in the portion shown in full lines.

I claim:

The ornamental design for a thermometer support, as shown and described.

JOSEPH J. MILAVEC.
